Primary Examiner — Cynthia Ramirez(57) **CLAIM**

The ornamental design for a mobile stairlift spiral, as shown and described.

DESCRIPTION

FIG. 1 is a front elevation view of a mobile stairlift spiral showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a perspective view thereof;

FIG. 8 is an enlarged view of the mobile stairlift spiral taken from the circle part in FIG. 5; and,

FIG. 9 is an enlarged view of the mobile stairlift spiral taken from the circle part in FIG. 2.

The broken lines in the figures are used to encircle enlarged areas and form no part of the claimed design.
